EYE PROTECTOR

William P. Biggs, Washington, D. C.

Application November 15, 1935, Serial No. 49,951

1 Claim. (Cl. 2-14)

(Granted under the act of March 3, 1883, as
amended April 30, 1928; 370 O. G. 757)

This invention relates to a goggle or the like and has among its several objects: To provide a cheap yet effective article of the type above mentioned; to provide an eye protector in which the lenses are readily insertable and removable but are nevertheless safely retained; to provide a goggle wherein the body and the straps for retaining the protector in operative position on the face of a wearer are made integrally; and to provide in the eye-cup a recess or trough for holding water that may, by a rapid forward inclination of the head, be swished over the inner surface of the lens to remove steam or other sight-obscuring materials adhering to the inner surface of the lens.

In the drawing:

Fig. 1 is a face view of an embodiment of the present invention;

Fig. 2 is an edge view with one eye-cup in section; and

Fig. 3 is an enlarged detail view of an eye-cup on the line 3-3, Fig. 1.

It is to be understood that the terms "lower", "outer", etc., as used hereinafter to designate relative positions refer to the positions of the parts of the device when it is being worn.

The eye protector embodying my present invention comprises a substantially flat body portion 4 which includes narrow, elongated strap members 5 adapted to pass around the back of the wearer's head and are secured together by any suitable means to retain the goggle in position on the face. The body and straps are normally flat, as may be seen in Fig. 2, and are of soft, very flexible rubber that readily adapts itself to the configuration of a wearer's face and clings closely so that dust and other deleterious matter are completely excluded from the eyes. The lateral edges of the body may be provided with beads 6 to prevent ready tearing of the soft rubber. The lower edge of the body is formed with a reentrant portion 7 to adapt it to the nose of a wearer and adjacent thereto the ribs 8 extend from the upper edge to the bead at the said portion.

The eye-cups 9 may be, and preferably are, formed integrally with the body 4. At the outer end of each eye-cup is a thickened bead 10, having in it an internal annular groove 11 which gives to this part a substantially U-shaped cross section. The beads 10 are of flexible rubber to

permit the ready insertion or removal of the lens 12 but, owing to the thickness of the bead, they are sufficiently rigid to retain the lenses safely while the protector is being worn. The edge of each lens 12 is formed with a double bevel, the portion 13 sloping toward the inner surface of the lens being considerably longer than is the portion 14 sloping toward the outer surface thereof, thereby facilitating the insertion of the lens into the eye-cup groove and its removal therefrom but providing a sufficient bearing surface between the outer face of the lens and the wall of groove 11 to insure against casual removal of the lens. The soft rubber in the bead 10 tends to adhere to the lens and so assists in the retention thereof.

In the lower side of each eye-cup 9 is formed a trough or recess 15, the wall of the eye-cup being thickened as shown at 16 to provide the requisite depth. Of course, if desired, the trough 15 might be formed by depressing the wall of the eye-cup below its normal contour and without the thickening as shown in Fig. 3. A small quantity of water may be placed in each trough 15 and when, during use, the lenses become fogged with steam or moisture from the wearer's face, or if any other sight-obscuring substance should gain access to the eye-cup and adhere to the lens, the inner surface of the lens may be washed by rapidly inclining the head forward to cause the water in the troughs 15 to swish over the lens and so remove the adhering material.

The invention described herein may be manufactured and used by or for the Government of the United States for governmental purposes without the payment of any royalties thereon or therefor.

I claim:

Eye-protecting goggles comprising a body portion having eye openings therethrough, means for securing the body portion over the eyes of a wearer, eye-cups secured over the eye openings in the body portion, a sight transparency closing the outer end of each eye-cup, a flange extending upwardly at the front of the base of each eye-cup and at the rear of the sight transparency, and a flange extending upwardly at the rear of the base of each eye-cup, said flanges providing a pocket for receiving condensation-clearing fluid.

WILLIAM P. BIGGS.
